M. OPPENHEIMER,
AUTOMATIC WINDMILL ATTACHMENT.

No. 357,288.

Patented Feb. 8, 1887.

UNITED STATES PATENT OFFICE.

MILTON OPPENHEIMER, OF SHENANDOAH, IOWA.

AUTOMATIC WINDMILL ATTACHMENT.

SPECIFICATION forming part of Letters Patent No. 357,288, dated February 8, 1887.

Application filed April 22, 1886. Serial No. 199,806. (No model.)

To all whom it may concern:

Be it known that I, MILTON OPPENHEIMER, a citizen of the United States, residing at Shenandoah, in the county of Page and State 5 of Iowa, have invented new and useful Improvements in Automatic Windmill Attachments, of which the following is a specification.

This invention relates to improvements in 10 regulating attachments for wind-wheels employed for pumping water into a tank, whereby the wind-wheel will be automatically thrown in or out of the wind, and its movement thereby continued or stopped, by the raising 15 and lowering of a float resting upon the water in the tank, acting in conjunction with suitable connections with the shifting devices and pump-plunger.

My invention consists of a vertically-sliding 20 rack-bar or sleeve, connected by cable, rod, or otherwise with the shifting or governing devices of the mill, a pivoted lever connected with and operated by the pump-plunger, having double pawls near its end, which 25 engage the racks of the sleeve and force the same down, and a spring-actuated lever keyed to the guide-bar, upon which the sleeve slides, and connected by cord or wire with the float in the tank.

30 The object designed to be accomplished by this invention is the automatic starting of the wheel when the tank needs refilling and the stopping of the same when said tank is full, so that the mill is only in operation when required for pumping.

Various forms of apparatus or attachments have been devised for automatically regulating pumping-windmills by the movement of a float in the water-tank acting through suitable 40 connections with the governor or shifting devices of the mill and pump-plunger; but these attachments have usually been so complicated as to be incapable of accomplishing the object sought, or soon got out of order and 45 became inoperative. An important point, therefore, in the present instance is the simplicity of construction and operation and fewness of parts composing the same, whereby there is little or no liability of the device becoming easily disordered.

For a better understanding of the details of

construction of my invention, reference must now be had to the accompanying drawings, in which similar letters of reference indicate like parts in the several views.

Figure 1 represents a view in elevation of a pumping-windmill supplied with my regulating attachment, the wind-wheel being shown as in the wind, the governor or shifting devices down out of action, and the sleeve of the 55 regulator as at the top of its movement. Fig. 2 is a similar view showing the wheel as out of the wind, with the shifting devices raised and the sleeve of the regulator as at the bottom of its movement. Fig. 3 is a detached 60 sectional view, in front elevation, of my improved attachment, the parts being in the positions shown in Fig. 1. Fig. 4 is a similar 65 view in side elevation, showing the position of the regulating attachment at the commencement of the movement or action thereof, the position of the wind-wheel, &c., being as in Fig. 1. Figs. 5 and 6 represent vertical 70 and transverse sectional views, respectively, through the sliding sleeve and its actuating 75 lever and pawls. Fig. 7 is a similar view to Fig. 4, showing the sleeve as at the bottom of its movement, and retained in this position by the spring-catch when the governor or 80 shifting devices are brought into action and the wheel thereby thrown out of the wind, as in Fig. 2. Fig. 8 is a plan view showing the relative positions of the parts of the regulating attachment when the water in the tank has been exhausted, the float being at the bottom of the tank, and the lever to which it is 85 connected drawn to one side, with the sleeve correspondingly turned, so as to avoid the spring-catch and thereby permit the counterpoise-weight of the governor to drop down, 90 thus throwing the vane around in position, and bringing the wheel into the wind, as in Fig. 1, and the sleeve at the top of its movement ready to be again engaged by the pawls. Fig. 9 is a similar view illustrating the same parts 95 in their relative positions when the float is in its elevated position, as in Fig. 1.

A A is the usual or any approved form of supporting frame-work for the mill, to the top of which are mounted the wind-wheel B and its 100 usual appurtenances, such as the hinged vane C and pivoted and weighted shifting device

or governor D, connected by the crank and link d^2 to and operating the vane C, for the purposes as will hereinafter more fully appear. E is the wire cable or rod connecting the 5 governor with the regulating attachment situated at the lower part of the frame.

F is the pump-plunger, operated in the usual manner by the crank-shaft of the wind-wheel. The regulator is composed of a rack bar or sleeve, S, mounted and sliding upon a square rod, R, secured in brackets $e\ e$ to a support, A', of the frame A. This sleeve is formed upon each of its edges with a series of teeth or racks, a and a' , which are engaged by spring-pawl d and d' , Fig. 5, mounted at one end of a lever, H, which lever is pivoted, as at h , within a bracket, I, also secured upon the frame A', and it is of such length as to extend laterally from said bracket I and engage the pump-plunger 20 F, as seen at f , by which motion is imparted thereto.

As before stated, the rod R, upon which the rack-sleeve S is mounted, is square and fits a square opening in the sleeve, as shown in Fig. 25, 6, so that the sleeve cannot turn upon the rod. This rod, however, is permitted to turn in its brackets or supports e by the movement of a lever, J, keyed to the top thereof, which lever in turn is connected by a cord or wire, j, with 30 the float J' in the tank T, and by the rising or falling of which float the said lever is operated, as will hereinafter appear.

K is a reacting spring attached at one of its ends to the top end of the rod R, and at its other 35 end pressing against the bracket e , whereby the said rod, when drawn around by the lever J, which tends to coil the spring, is returned to its normal position by the resistance of said spring. Upon the rear edge of the rack a , and 40 upon the front edge of the rack a' , Fig. 6, are formed shoulders 1 and 2, respectively, whereby the turning of the sleeve as well as rod is prevented so long as the pawls are engaged with said racks; but to permit the passage of the 45 sleeve past the pawls the top portion of the sleeve is made round or free from shoulders, as seen at a^2 , Fig. 3, so that the said sleeve can only be turned around to throw the pawls out of position when at the bottom of its movement, when the pawls will be beyond the racks 50 and upon the round part, as seen in Fig. 7.

M is a spring-catch, Figs. 4 and 7, which, when the sleeve is at the bottom of its travel, engages over a projection or catch, m, formed 55 on the bottom end of the sleeve, whereby the said sleeve is held down at the end of its lower movement, from which position it can only be released by the turning of the said sleeve, so as to bring the projection m out of contact with 60 the catch, and thereby permit the sleeve to assume its elevated position.

The operation is as follows: Supposing the tank to be empty, the float will be at the bottom thereof, with the lever J drawn around 65 and the sleeve S at the top of the rod R, and partially turned around, as shown in Fig. 8. The governor D will also be down and out of

action, but the vane C will be around in position so as to shift the wheel into the wind. The said wheel will therefore now begin to revolve, and through its crank-shaft operate the pump-plunger F and commence pumping and refilling the tank. The plunger being connected with the outer end of the lever H, said lever is brought into play and the spring-pawl d at its opposite end alternately raised and depressed. As before stated, the sleeve S will be at the top of the rod R and partially turned around, so that the pawls d will rest upon the shouldered or smooth portion 3 and 3, and do not engage the racks a and a' , so that at first there is no action or movement of the sleeve, which remains idle until the water begins to fill the tank and raise the float upward, when, the resilience of the spring K acting upon the rod R, said rod, together with the sleeve S, is brought gradually around into its normal position, when the pawls will drop into the racks and the operation of depressing the sleeve will now be commenced, as seen in Figs. 3 and 5. The tension of the spring K is only just sufficient to return the lever J and sleeve S back to their normal position, as in Fig. 9, when the weight of the float is taken therefrom, so that said spring cannot act until the water as it enters the tank acts to raise the float and take the weight thereof from the spring, when the parts may return to their normal position. The length of the sleeve also and the racks thereon is such relatively to the movement of the shifting devices or governor that when the governor is elevated to the proper position to bring the vane around, and thereby cause the wheel to come into the wind, the said sleeve 105 will be at the bottom of its path and the pawls at the last tooth of the rack, and when the governor is down the sleeve will be elevated, with the pawls opposite the lower notches in the rack. Supposing now, that sufficient water has entered the tank to raise the float up and permit the turning of the sleeve back to its right position, as in Fig. 9, for the engagement of the pawls with its racks, then, as seen in Fig. 3, the said pawls by their action 115 immediately commence to depress the sleeve, and through the cord or rod E, which is attached at one end to the governor and at the other to the said sleeve, as seen at l , Fig. 4, the said governor is acted upon and drawn upward in position, and through it the vane is brought around so as to shift the wheel out of the wind and cause its movement to cease, this being accomplished by the time the pawls are at the top of the rack, and the shoulder or stop m of the sleeve has engaged the spring-catch M, as in Fig. 7. The mill has now ceased 125 its movement, and the wheel, governor, and vane will be shown, as in Fig. 7, with the sleeve at the bottom of its travel, and the tank full of water with the float resting upon it.

As the water is exhausted from the tank the float follows the same, and, drawing upon the lever J, turns the rod R, and through it the 130

sleeve S, which disengages it from the catch m, when the counter-weight of the governor exerts itself, and by dropping down raises the sleeve to its first position, and at the same time shifts the vane around so as to bring the wheel into the wind, when the pumping action is again commenced, as before explained. Thus the shifting of the wind-wheel in and out of the wind is performed automatically by the raising and falling of a float in the tank through the intervention of a vertically-sliding rack-bar connected with the governor and operated by pawls which receive their motion from the mill-plunger.

15 The sleeve-rack has the smooth sides 3 3 between the racks, upon which the pawls ride when the sleeve is raised to keep them clear of the racks, and the sleeve may be made without the continuous shoulders along the rack.

20 I claim—

1. In an automatic regulating attachment for windmills, the combination of the shifting-cord E and a vertical rod, R, having pivot-bearings in the fixed frame, with a double rack-sleeve having a vertical movement upon said rod, a double pawl-lever having a fixed pivoted relation to said slide-rack, the pump-rod, and means, substantially as described, for connecting said vertical rod with the float, where- 25 by the latter is caused to turn the said vertical rod on its pivot-bearings to turn the double slide-rack out of engagement with its double operating-pawls, substantially as described, for the purpose specified.

30 2. In an automatic regulating attachment for windmills, in combination with the shifting-rod and pump-plunger of the mill, the

square rod R of the regulating attachment, having a reacting spring at its end, sleeve S, sliding upon said rod and having racks upon 40 its sides, lever H, with pawls d d, and lever J, keyed to the rod R and connected by cord with the float in the tank, as shown and described.

3. The sleeve S, having racks upon its side and formed with shoulders 1 and 2 adjacent 45 said racks, and a round portion, a², combined with the lever H, pawls d d, and lever J, operated by the float in the water-tank, whereby the said sleeve is prevented from turning, as described and shown.

4. In combination with the sleeve S, having racks upon each side, shoulders adjacent thereto, and a round or smooth portion at the top, the projection or stop m, formed at the bottom of the sleeve, and spring-catch M, adapted to 55 engage said stop, as described and shown.

5. The combination, with the windmill wheel, vane, weighted governor, pumping-plunger, and shifting-rod, of the automatic attachment composed of square rod R, adapted to turn in 60 its bearings, sliding sleeve S, having racks upon its side, lever H, with pawls d d, lever J, reacting spring K, catch m M, cord j, and float J', all arranged as described and shown, whereby the wind-wheel is automatically 65 brought in or out of the wind by the rising or falling of the water in the tank.

In testimony whereof I have hereunto set my hand in the presence of two subscribing witnesses.

MILTON OPPENHEIMER.
